UNITED STATES PATENT OFFICE.

IRA A. STORER, OF SAN FRANCISCO, CALIFORNIA.

BUNTLINE FOR REEFING SAILS.

SPECIFICATION forming part of Letters Patent No. 272,171, dated February 13, 1883.

Application filed October 30, 1882. (No model.)

To all whom it may concern:

Be it known that I, IRA A. STORER, of San Francisco, county of San Francisco, State of California, have invented an Improved Sail and Gear; and I hereby declare the following to be a full, clear, and exact description thereof.

My invention relates to certain improvements in sails and their running-gear; and it consists in the addition of certain lines, which I call "purchase-buntlines," whereby a portion of the sail may be hauled up to render the clewing up of the remainder an easier matter, and in certain strengthening-ropes upon the forward part of the sail, as will hereinafter fully appear.

My invention will be best illustrated in its application to a top-gallant sail, and accordingly I have herein represented that sail and the gear appertaining thereto.

When a sail is very large, as these sails are, great difficulty is found in clewing up. This has led to the placing upon large vessels of two yards—the upper and lower top-gallant yards—and of bending on each a top-gallant sail—upper and lower. These sails are each worked by its own set of running-gear, and the advantage obtained is in dividing a large sail into two smaller ones, each of which is comparatively easy to be handled; but the obvious objections to the plan are, that a sail is more effective as a single sail than when the same amount of canvas is made into two sails, that there is too much weight aloft, that it requires too much gear, and that two yards and gearing are more expensive than one.

The object of my invention is to retain the single large sail, and by a proper arrangement of additional running-gear avoid the difficulty of clewing up, and also, by a proper strengthening of the sail, to economize in the character of the canvas and still have the sail as strong as before.

Referring to the accompanying drawings, Figure 1 is a view of the after part of the sail, showing the purchase-buntlines in connection with the usual running-rigging. Fig. 2 is a view of the forward part of the sail, showing the strengthening-ropes and a part of the purchase-buntlines. Fig. 3 is a view of the after part of the sail, showing the purchase-buntlines alone for better inspection.

Let A represent the deck of a vessel, B the upper portion or head of the top-mast, C the top-gallant mast, D the top-gallant yard, E the top-sail yard, and F the top-mast cross-tree with outriggers f. I have here shown also the top-gallant back-stays c and the top-mast back-stays b.

S represents the top-gallant sail bent to the top-gallant yard, and its clews hauled to the sheave-holes of the top-sail yard by the sheets a.

Q are the halyards of the top-gallant yard.

P represents a pin-rail, which for convenience I here show as a means of securing the running-rigging.

The innermost ropes, d, are the clew-lines. These pass up through the cross-tree through block t; but instead of passing thence directly to and being secured to the clews, they pass through a block, t', attached to the clews, up to another, t'', hung under the top-gallant yard, and down again to block t', to which they are secured. The block t'' is placed some distance out on the yard, with what object will be hereinafter fully explained. The next ropes are the buntlines e. These pass up and are suitably guided over the top of the sail and down to its bunt on forward part of sail. The next are the leech-lines l, which also are suitably carried over on forward side of sail and to the leech-rope on each side. These are the ordinary running-rigging of this sail.

When there is little wind or a calm, the sail can be clewed up in the usual manner without difficulty; but when the wind is high it is a difficult matter to handle so much sail.

When the sheets are let go and the yard clewed down on the cap, the sail bellies out so much that it is difficult to clew it up. To remedy this difficulty I haul up a portion of the sail snug under the top-gallant yard, thus reducing the stretch of canvas and allowing the remaining portion to be handled by the regular running-rigging. The outermost ropes, h, I call the "purchase-buntlines." These will be seen to advantage in Fig. 3. They consist of Manila rope up to a block, w, on each side, through which they pass down to and are secured to the outriggers f of the cross-tree. This only shows one way of getting the purchase, though any suitable arrangement of tackle would answer. Their continuations

(marked *h'*) consist of wire rope. Of these there are two legs on each side, both attached to the block *w*. One leg of these lines on each side passes up through the uppersheave of a fiddle-block, *x*, thence out to a point near the ends of the top-gallant yard when the sail is set, where they are continued as chain and pass down through an iron cleat on the yard-arms to a point about one-third of the distance down the sail, and are secured to the leech-ropes, as shown. The other leg of the wire passes up on each side through the lowersheave of fiddle-block *x*, thence out to the quarter of the yard, through a cleat on the forward side of the yard, and down abaft the sail to a point on the same horizontal line with the points of attachments of the other legs on the leech. Here they are toggled through an eye, *y*, which is made by carrying the upper ends of the vertical ropes *R'* (explained hereinafter) through the sail.

Now, in handling the sail, the first thing is to clew the yard down on the cap, as usual, then man the purchase-buntlines *h*, together with the clew-lines and the ordinary buntline, let go the sheets, and clew up the sail. The effect of the purchase-buntlines is to haul up about one-third of the sail close under the yard. Comparatively little wind can get in it, as it is drawn snug up. This leaves a portion of the sail to handle with the other gear. The clew-lines haul up the clews to the block *t*², which by being out a little distance on the yard leave slack leech for furling the sail.

The whole advantage of these purchase-buntlines is to take up sufficient of the sail to render it easy to handle the remainder. To sheet the sail home, let go all the gear excepting the purchase-buntlines. These, by holding a portion of the sail to the yard, render the hauling of the sheets home very much easier, especially in a strong breeze.

Across the forward side of the sail, on a line above its center, is roped on a band a small hemp rope, *R*, horizontally, and two similar ropes, *R'*, vertically from said rope *R* to the 45 foot of the sail—one on each side of the center. The tops of these ropes *R'* are passed through the sail and form eyes *y*, for securing a leg of the purchase-buntlines. These are strengthening-ropes and serve a double object—namely, 50 strengthen the sail to prevent it from splitting in hauling up the purchase-buntlines, and enable me to use lighter canvas and have the sail equally strong.

Having thus described my invention, what I 55 claim as new, and desire to secure by Letters Patent, is—

1. In combination with a sail and running-rigging to haul it up, the purchase-buntlines *h* and *h'*, the latter having two legs, one of 60 which is attached to the leech on each side below the yard, and the other attached to the after part of the sail on the same line as the first legs are attached, and on each side of the vertical center of the sail, substantially as and 65 for the purpose herein described.

2. The sail *S*, having the horizontal strengthening-rope *R* and the vertical strengthening-ropes *R'*, and running-rigging to haul it up to the yard, in combination with the purchase- 70 buntlines *h* and *h'*, the legs of the latter being attached to the leech on each side at the ends of rope *R*, as shown, and to the after part of the sail, to the tops of the ropes *R'*, all arranged substantially as and for the purpose herein described. 75

In witness whereof I hereunto set my hand.

IRA A. STORER.
